SLUSH PUMP PISTON

Raymond G. Taylor, Jr., Santa Monica, Calif.

Application April 4, 1949, Serial No. 85,357

12 Claims. (Cl. 309—4)

1

The present invention relates to pistons in general and particularly to a piston for slush pumps and the like which incorporates improved sealing or packing means. More particularly the invention comprises a slush pump piston in which the sealing cups, washers, or packings are constructed, arranged, and retained in a novel manner to provide positive sealing, reduced friction, and long life.

Slush pumps are used to circulate the slush or drilling mud in well-drilling operations. Possibly the drilling of oil wells is the most common and best known type of operation in which they find use. The mud must at times be pumped to tremendous depths and at pressures which may exceed a thousand pounds per square inch. In the pump a reciprocating piston operates against the maximum pressure in the working stroke and against a reduced pressure, which may be below atmospheric, on the return stroke. A positive seal must be maintained to handle the tremendous pressures involved, and it is essential for efficient and economical operation that the piston life be of reasonable length.

The pump piston acts directly against the abrasive mud or slush within the cylinder and travels at high speeds. Metal-to-metal contact using the liquid abrasive as a lubricant is impossible, and conventional slush pump pistons have long embodied non-metallic cylinder-contacting packings, seals, or washers, usually of a resilient material. While the broad principle of using such resilient members is accepted, it has been found that there is a great latitude in their operating effectiveness depending upon their characteristics. The present invention is directed toward an improved slush pump piston construction which is characterized by its improved operation and longer life made possible by variants from the conventional designs and which cooperate in a new and novel manner.

With an appreciation of the problems present in the field of slush pumps and particularly those problems inherently present in the piston unit of such pumps, it is an object of the present invention to provide a piston adapted for use in slush pumps and the like in which the cylinder-contacting sealing means are so constructed that the area of sealing contact in which the piston contacts the enclosing cylinder varies with the pressures present.

It is another object of the invention to provide a slush pump piston unit in which there is provided one or more resilient sealing washers making contact with the enclosing pump cylinder

2

and which are so constructed that the limits of their sealing areas move progressively and longitudinally along their peripheral surfaces with variations in the pressures acting thereagainst.

Still another object of the invention is to provide a piston for slush pumps and the like in which a sealing member adapted to make contact with an enclosing cylinder incorporates portions of different resiliency so constructed and arranged that as the pressure acting against the unit increases the portion of the unit of lesser resilience assumes increased importance in the sealing function.

Still another object of the invention is to provide a slush pump piston in which cylinder-contacting surfaces provided by materials of different resiliency are so arranged that the pressure-sealing area advances progressively along the element into the area provided by the material of lesser resilience as the pressure increases.

A further object of the invention is to provide a piston for slush pumps and the like in which the sealing cup is so contoured on its pressure-receiving face as to reduce the sealing pressure between its more resilient portion and the enclosing cylinder as the pressure increases to reduce effectively the frictional wear of that portion.

A further object of the invention is to provide an improved slush pump piston in which the parts are retained in their assembled relationship by improved readily disengaged retaining means.

These and other more specific objects will appear upon reading the following specification and claims and upon considering in connection therewith the attached drawing to which they relate.

Referring now to the drawing in which preferred embodiments of the invention are illustrated:

Figure 1 is a partial longitudinal section through the cylinder of a slush pump within which is positioned a piston constructed in accordance with the present invention which is itself partially shown in section;

Figure 2 is a partial section through a piston with the sealing up in its normal uncompressed condition and illustrated with respect to the surface of a cylinder which the piston is designed to enter;

Figure 3 is a view similar to Figure 2 with the piston positioned within an enclosing cylinder wall and with relatively small pressure acting thereagainst;

Figure 4 is a view similar to Figure 3 and illus-

trates the longitudinal shift of the area of sealing contact of the piston cup with increased pressure acting against the unit;

Figure 5 is a partial view of a piston similar to that illustrated in Figure 1 but incorporating modified cup-retaining means; and

Figure 6 is a view looking in the direction of the arrows upon the line 6—6 of Figure 5.

The piston rod of a slush pump is indicated in the drawing by the reference character 11 and is connected to a suitable source of power by which it is reciprocated longitudinally within an enclosing cylinder 12. Rod 11 is tapered at 13 adjacent its end to receive the piston comprising the present invention and its extreme end is exteriorly threaded at 14 to seat an internally threaded nut 16 which functions to hold the piston in place on its tapered seat.

The piston proper comprises a cylindrical body or hub 17 provided with a tapered bore 18, of a size to seat upon the tapered portion 13 of rod 11, and with a centrally positioned radially extending flange 19, the external diameter of which is sufficiently less than the internal diameter of cylinder 12 as to leave approximately $\frac{1}{64}$ inch clearance. This exact figure is not of the essence, it being important only that the body does not contact the cylinder. An internal circular groove 21 is provided in the body 17 opening into tapered bore 18 and seats a sealing O ring 22, as illustrated in Figure 1, to prevent pressure leakage through the bore 18. Piston body 17 is made of a rigid material, preferably metal, and serves as the supporting structure for a pair of cup washers or packings, generally indicated by the reference character 25, positioned upon opposite sides of its flange 19. It is in the construction of members 25 and in the retaining means by which they are removably secured to the body 17 that the present invention resides. The members 25 and their retaining means upon opposite sides of flange 19 are duplicates and only one set will be described.

Each washer or packing 25 comprises a disk-like portion 26 and an adjacent outer portion 27 integral therewith and formed principally as a longitudinally extending flange. Portion 26 in a preferred form comprises a disk formed of adjacent flat canvas rings, the interstices of which are filled with rubber which is preferably natural rubber. Outer part 27, on the other hand, is formed entirely of resilient material and is much more resilient than 26.

A rigid backing plate 29 is bonded, as by being vulcanized, to the inner face of part 26 and lies against the adjacent radial face of body flange 19. The plate and the portion 26 have the same radial extent and lie approximately $\frac{3}{32}$ inch within the periphery of flange 19. Here again the exact distance is not of the essence but instead it is important that the radial extension be less than that of the flange. In a preferred relationship the portion 26 is exteriorly frusto conical with its greatest diameter adjacent plate 29. Plate 29 does not extend inwardly for the entire radial extent of flange 19 and portion 26 extends thereunder and adjacent the flange at 31. Another feature of interest and importance lies in the fact that radially beyond a circle concentric to shaft 11 and including the point indicated by the reference character 32 each washer portion 26 flares outwardly from the plate 29 so that its outer peripheral surface is of greater extent than its inner surface. This provides a

greater surface area for portion 26 apposing the enclosing cylinder than would otherwise be the case and makes for economy in the use of the material of portion 26 which is relatively expensive rubber-covered fabric at each layer.

Turning now to packing portion 27 which is of greater resilience than portion 26 it is seen to extend radially adjacent the inner portion of part 26 and to be formed adjacent body 17 as a longitudinally extending circular lip 34. At a point spaced radially from the body 26 by a distance substantially equal to that of point 32 body 27 in any radial plane is inclined outwardly as a surface 36 which terminates in a narrow radially extending surface 37. The latter is connected by a surface 38, which makes an angle of about forty-five degrees with it, to the top surface 39 of packing portion 27 extending inwardly to merge with the peripheral surface of portion 26. The surfaces 36, 37, 38, and 39 form the exterior of a longitudinally extending circular tapered flange which normally in its un-compressed, undeformed condition has a greater diameter at its outer end than the cylinder 12 within which the piston is intended to fit. Figure 2, in which the dot dash line indicates the inner surface of cylinder 12, illustrates the oversize of the packing while Figures 3 and 4 show it positioned within the cylinder and deformed under different pressure conditions.

Each packing 25 is removably retained against longitudinal displacement upon the body or hub 17 and against the central flange 19 by manually adjustable locking means comprising in each instance a flat rigid circular abutment plate 41 in contact with the flat radially extending surface of washer portion 27. Plate 41 is contoured to conform to the curvature of portion 27 as it merges from its radially extending flat face into the inclined surface 36. Plate 41 is forced against sealing member 25 by a plurality of arcuately spaced headed bolts 43 carried by a ring 44 closely encircling body 17. The ring is formed with a beveled edge 46 abutting a garter-type coil spring 47 expanded in a groove 48 in the surface of body 17. The threaded portion of each bolt 43 is of such length that with its head in contact with the outer surface of ring 44 and the latter abutting the retaining spring 47 the plate 41 will be forced against the adjacent packing 25 with the desired retaining pressure.

The assembly of the piston unit constructed in accordance with the present invention is a simple operation accomplished, of course, with the piston outside of the cylinder and preferably displaced from the rod 11. Let it be assumed that it is desired to place new packings 25 upon the piston body 17. As the operation is identical for each packing the positioning of only one need be described. The packing or washer, which is cup-like in shape and centrally bored, is advanced upon the end of the body 17 until its backing plate 29 abuts the body flange 19. The abutting plate 41 is then seated upon the cup, being properly centered by the lip 34 which extends into the bore of the plate which is sized to receive it. The outer and adjacent edge of plate 41 is curved to conform to the curvature of the adjacent cup portion 27 where its inclined surface 36 merges with its flat radial surface. The clamping ring 44 is then moved axially into position with the bolts 43, of which there are a plurality spaced arcuately, in a somewhat withdrawn position. The retaining

coil spring 48 is expanded around the end of body 17 and is slid therealong until it seats in the circumferential groove 48. With the spring seated the clamping ring 44 cannot be displaced longitudinally from the piston body. The individual bolts 43 are then rotated to advance them through ring 44 and their forward ends into contact with abutment plate 41. The bodies of the bolts are of such a length that with each bolt tightened until its head contacts the ring 44 a predetermined and desired clamping pressure is exerted against plate 41 which holds the entire cup 25, and primarily the rigid metallic plate 29, against the hub flange 19.

With both cups 25 secured in place upon the piston body 17 and with the sealing O ring 22 positioned within its groove 21 the piston is ready to be positioned upon the actuating rod 11. As described, the end 13 of the rod is tapered as is the interior bore 18 of the piston body. The piston is advanced longitudinally onto the rod, its end with the larger opening being in advance, until it seats upon the tapered end 13. The interiorly threaded nut 16 after being rotated onto the threaded end 14 of the rod and advanced until it contacts the adjacent end of body 17 is then further advanced sufficiently to wedge the piston body onto the rod in rigid fixed relationship. Leakage between the rod and the piston body is prevented not only by the tight fit of the parts but also by the presence of the O ring 22 which is compressed within its groove 21.

The next step comprises the positioning of the piston within the cylinder 12. In the conventional slush pump piston design the packing is formed with a relatively sharp edge or lip at the forward portion of its flange. This edge or lip abuts the cylinder wall and all too frequently in sliding the piston into the cylinder, and also in its reciprocation therein, the lip is turned back between the flange and the cylinder resulting in tearing, excessive friction, and undue wear. This difficulty is entirely eliminated by the packing constructed in accordance with the present invention. The conventional flange, the shape of which is seen by referring to Figure 2 in which the dotted line C indicates the normal underside of the flange, has been thickened to provide an outer lip portion which includes a beveled angularly inclined surface 38 and a radial surface 37. The lip itself is seen to be greatly thicker than the normal lip and the inclination of the beveled surface 38 prevents any tendency to wedge it rearwardly and back between the cylinder and the flange itself. Outside of the cylinder 12 the piston cup 25 normally assumes a maximum diameter which is larger than the internal diameter of the cylinder, as illustrated in Figure 2, so that upon being inserted in the cylinder the cup flanges are forced radially inwardly. The cup portion 26 is of smaller diameter than the cylinder and it is the flange portion of the part 27 which makes the sealing contact which largely is at the outer end thereof, as illustrated in Figure 3. Substantially this same relationship exists when small pressures are acting against the piston.

With the piston assembled and positioned within the cylinder as described and the cylinder properly oriented in the pump the unit is ready for operation, the manner of which will now be described. Under the control of valves forming no part of the invention slush or mud is drawn into the cylinder 12 upon each side of the piston during a suction stroke to be placed under pres-

sure and forced therefrom during each compression or working stroke. During a suction stroke the pressure acting against a piston cup 25 will be very small, even atmospheric pressure or less, and the contact made by the cup with the enclosing cylinder will be largely the result of its own inherent resilience forcing it outwardly. Under these conditions it is the outer end of the cup flange, that is, the outer or lip portion of the part 27, which contacts and provides the major sealing effect with the cylinder wall, in the manner illustrated in Figure 3. The area in contact with the wall is reduced to a minimum providing the double advantage of reduced friction and reduced wear. In the compression or working stroke during which the fluid is placed under pressure by the advance of the piston, the advancing cup is placed under tremendous pressures which may vary between three hundred and fifteen hundred pounds per square inch or more. These pressures, of course, are exerted in all directions within the cylinder and against all exposed piston surfaces. With the pressure at a minimum the sealing contact of the cup with the cylinder will be as illustrated in Figure 3 but as the piston moves forwardly in its working stroke and the pressure of the fluid increases a change takes place. It might be thought that with the increase in pressure the extreme edge or lip of the flange of cup portion 27 would be forced with greater pressure against the enclosing cylinder wall but such is not the case. With the cup designed as described it has been determined that with the increase in pressure the cylindrical area of contact with maximum pressure between the cup and the enclosing cylinder wall actually advances longitudinally and toward the flange 19. At the lower pressures the maximum sealing pressure is at the outer or lip portion of the flange and as it increases the ring area of maximum sealing pressure moves inwardly until at the extreme pressures it is the peripheral area of a less resilient cup portion 26 which provides the maximum sealing effect. In Figure 4 this relationship is illustrated in an exaggerated manner, the dotted line indicating a sealing position corresponding to a still higher pressure. Actually in the high pressure relationship of Figure 4 the outer portion of the packing is in contact with the enclosing cylinder being separated therefrom only by a thin lubricating film of fluid. The showing of the drawing is intended to emphasize the fact that the maximum sealing pressure and effect has shifted longitudinally and not that the portion 27 is actually spaced physically from the enclosing cylinder. It appears that with the increase in pressure the ability of the more flexible resilient body 27 to provide a positive seal decreases and the pressure of the fluid makes itself felt further along the cup length. It is accurate to state that the cylindrical area of maximum sealing effect between the packing and the cylinder travels axially or longitudinally inwardly along the packing and toward the body flange 19 as the operating pressures increase. It cannot be said positively that a straight line relationship exists but the relationship is as described. The expanding tendency of the pressure acting upon the outer lip of the body portion 27 is minimized by the apposing component of pressure acting upon the beveled surface 38. The same result follows along the length of the cup flange in which fluid leakage brings the cylinder fluid pressure directly between the packing and the cylinder.

As the piston reciprocates within the cylinder the cups upon the opposite sides thereof are placed under compression alternately and the sealing areas travel longitudinally as described. As the sole lubricant present is the fluid itself the lubricating action is aided by the beveled surface 38 which tends to work a thin film of fluid into and between the cylinder and the flange rather than to wipe it from the cylinder wall in the manner of a squeegee as do the conventional sharp-lipped cups.

Turning now to Figures 5 and 6 in particular, a modified construction of the present invention is illustrated which is to be understood as being identical to that first described except as specifically pointed out. Piston body 17 and sealing cup or packing 25 can be understood to the same except that the packing ring 22 is omitted and in place of the semi-circular-sectioned grooves 48 seating the springs 47 in the first embodiment grooves 61 having mutually perpendicular walls are substituted. The abutment plate 41 is again positioned against the exterior radial plane surface of the cup 25 and is forced thereagainst by a plurality of arcuately spaced headed bolts 62 the forward ends of which extend into unthreaded recessed seats 63 in the plate. The bolts are threadedly seated in a clamping ring 64 formed of two semi-circular sections narrowed along their inner peripheral edges which seat in the grooves 61. The extension of the forward ends of the bolts 62 into the seats 63 secured in plate 41 effectively prevents radial separation of the ring sections. Lock washers 66 are preferably placed between the head of each bolt 62 and the clamping ring 64. With the exception of the retaining means described this construction is identical to that first described both in structure and in operation.

The packing or sealing cup comprising an important part of the present invention may be constructed in different manners. One preferred method comprises placing the plate 29 in a mold with the portion 26 in the form of a flat disk positioned thereon. A relatively great pressure is then exerted upon the top of disk 26 by a die which is flat for a portion of its surface and then inclined so that the pressure exerted upon the outer portion of the disk is less than upon the inner portion. The force compresses the disk 26 forcing it radially inside the inner radius of plate 29 into the underlying shoulder 31. The pressure also compresses the central portion of the disk to a greater extent than the outer portion which is flared outwardly to conform to the curvature of the die. The resulting portion 26 has a section as illustrated in the drawing. The resilient part 27 is then molded in place and in the operation the plate 29 is vulcanized to the adjacent cup portion 26 to make a unitary integral construction as described.

While the particular apparatus herein shown and described in detail is fully capable of attaining the objects and providing the advantages hereinbefore stated, it is to be understood that it is merely illustrative of the presently preferred embodiments of the invention and that no limitations are intended to the details of construction or design herein shown other than as defined in the appended claims.

I claim:

1. In a sealing washer for a slush pump piston of the type having a hub body formed with a radially extending flange, a sealing washer adapted to be positioned at the side of said flange

and including peripheral surfaces adapted to make sealing contact with an enclosing cylinder and an end surface facing the interior of said cylinder, said washer being formed of resilient

5 parts of different resiliencies bonded at the part of least resilience to a flat radial backing plate adapted to abut said flange, said part of least resilience having a peripheral surface normally less in diameter than the diameter of said cylinder, the part of said washer adjacent said part of least resilience being of greater resilience and having a longitudinally extended flange formed with frusto-conical inner and outer surfaces, the outer surface varying in diameter from 10 a minimum less than to a maximum greater than the diameter of said cylinder, the inner surface being spaced longitudinally from said part of least resilience and radially within said outer surface, a radial surface extending radially outwardly from the said frusto-conical inner surface, and a surface inclined radially outwardly and longitudinally toward said backing plate connecting the said radial surface to said frusto-conical outer surface.

15 2. The construction recited in claim 1 characterized in that said surface inclined radially outwardly and longitudinally toward said backing plate makes an angle of approximately forty-five degrees with a plane normal to the axis of the piston in its operative relationship.

30 3. The construction recited in claim 1 characterized in that said surface inclined radially outwardly and longitudinally toward said backing plate makes an obtuse angle with said frusto-conical outer surface.

35 4. In a sealing washer for a slush pump piston of the type having a hub body formed with a radially extending flange, a sealing washer adapted to be positioned at the side of said flange

40 including peripheral surfaces adapted to make sealing contact with an enclosing cylinder and pressure-receiving surfaces exposed to the interior of a cylinder enclosing said piston and arranged as to receive radial, longitudinal and 45 mutually cancellative forces from a pressure existing in said cylinder, said pressure-receiving surfaces including a frusto-conical surface positioned radially within said peripheral surfaces and extended longitudinally therebeyond, said surface being adapted to receive pressure-exerted forces directed radially outward and longitudinally, a cylindrical end surface extended radially at the outer end of said frusto-conical surface

50 adapted to receive a pressure-exerted longitudinal force, and a relatively narrow frusto-conical surface connecting said cylindrical end surface and the outer end of said peripheral surfaces and adapted to receive pressure-exerted forces directed radially inward and longitudinally, the said radially outward and radially inward forces being cancellative to reduce the sealing pressure exerted on said peripheral surfaces.

placement relative to said body upon the adjustment of said bolts.

6. The construction recited in claim 5 characterized in that said groove is semi-circular in section and in that said retaining means comprises a continuous coil spring.

7. In a slush pump piston, a hub body formed with a radially extending flange, a sealing washer positioned at the side of said flange and including peripheral surfaces adapted to make sealing contact with an enclosing cylinder and an end surface facing the interior of said cylinder, said washer being formed of resilient parts of different resiliencies bonded at the part of least resilience to a flat radial backing plate abutting said flange, said part of least resilience having a peripheral surface normally less in diameter than the diameter of said cylinder, the part of said washer adjacent said part of least resilience being of greater resilience and having a longitudinally extended flange formed with frusto-conical inner and outer surfaces, the outer surface varying in diameter from a minimum less than to a maximum greater than the diameter of said cylinder, the inner surface being spaced longitudinally from said part of least resilience and radially within said outer surface, a radial surface extending radially outwardly from the said frusto-conical inner surface, a surface inclined radially outwardly and longitudinally toward said backing plate connecting the said radial surface to said frusto-conical outer surface, an abutment plate in contact with the end surface of said washer radially within the inner frusto-conical surface of said flange, a backing ring encircling said body adjacent said abutment plate and fixed against longitudinal displacement therefrom, and a plurality of headed bolts carried by said ring adjustable toward and from said abutment plate to force said washer against said flange radially within said flange.

8. The construction recited in claim 7 characterized in that said surface inclined radially outwardly and longitudinally toward said backing plate makes an angle of approximately forty-five degrees with a plane normal to the axis of the piston in its operative relationship.

9. The construction recited in claim 7 characterized in that said surface inclined radially outwardly and longitudinally toward said backing plate makes an obtuse angle with said frusto-conical outer surface.

10. In a slush pump piston, a hub body formed with a radially extending flange, a sealing washer positioned at the side of said flange including peripheral surfaces adapted to make sealing contact with an enclosing cylinder and pressure-receiving surfaces exposed to the interior of a cylinder enclosing said piston and arranged as to receive radial, longitudinal and mutually cancellative forces from a pressure existing in said cylinder, said pressure-receiving surface including a frusto-conical surface positioned radially within said peripheral surfaces and extended longitudinally therebeyond and a radial surface positioned radially inside said frusto-conical surface, said frusto-conical surface being adapted to receive pressure-exerted forces directed radially outward and longitudinally, a cylindrical end surface extended radially at the outer end of said

frusto-conical surface adapted to receive a pressure-exerted longitudinal force, and a relatively narrow frusto-conical surface connecting said cylindrical end surface and the outer end of said peripheral surfaces and adapted to receive pressure-exerted forces directed radially inward and longitudinally, the said radially outward and radially inward forces being cancellative to reduce the sealing pressure exerted on said peripheral surfaces, and an abutment plate in contact with said radial surface, a backing ring encircling said body adjacent said abutment plate and fixed against longitudinal displacement therefrom, and a plurality of headed bolts carried by said ring adjustable toward and from said abutment plate to force said washer against said flange within said flange.

11. In a slush pump piston, a cylindrical bored body formed with a radial flange and with a circumferential groove spaced therefrom, a sealing gasket seated concentrically on said body at one side of said flange in abutting contact therewith, an abutment plate in contact with the side of said gasket spaced from said flange, and a locking ring encircling said body adjacent said groove and fixed relative to said body to prevent longitudinal displacement from said flange and carrying a plurality of headed bolts adjustable toward and from said abutment plate to force said gasket against said flange.

12. In a slush pump piston, a cylindrical bored body formed with a radial flange and with a circumferential groove spaced therefrom, a sealing gasket seated concentrically on said body at one side of said flange in abutting contact therewith, an abutment plate in contact with the side of said gasket spaced from said flange, a locking ring encircling said body adjacent said groove and carrying a plurality of headed bolts adjustable toward and from said abutment plate to force said gasket against said flange, the inner peripheral edge of said ring being adapted to seat in said groove to prevent its longitudinal displacement upon the adjustment of said bolts, characterized in that said ring is split to enable it to be removed with said bolts in a loosened condition and in that said abutment plate is formed with seats for the contacting ends of said bolts to prevent the radial displacement of said ring with said bolts tightened.
